UNITED STATES PATENT OFFICE

2,397,721

WINDOW CONSTRUCTION

Siegfried E. Blessin, Mertztown, Pa.

Application January 27, 1944, Serial No. 519,960

2 Claims. (Cl. 292—254)

This invention relates to improvements in window constructions.

It is an object of the invention to provide an improved window construction wherein the sash frame may be vertically reciprocated to open and close the window with a minimum of effort and in a positive manner.

A further object of the invention is to provide a window construction wherein the sash frame is normally positively and frictionally sealed in the window casing.

A further object is to provide a window construction having spring-urged means to normally seal the vertical edges of the window and roller means adapted to displace the spring means for elevating and lowering the sash frame.

These and other advantageous objects, which will later appear, are accomplished by the simple and practical construction, combination and arrangement of parts hereinafter described and exhibited in the accompanying drawing, in which:

Fig. 1 is a fragmentary vertical elevational view of one of the vertical portions of a sash frame provided with the structure of my invention, shown in normal, sealed position, and

Fig. 2 is an enlarged fragmentary view taken at the lower part of Fig. 1, the operative parts being shown in position to permit the sash to be vertically reciprocated.

Fig. 3 is a transverse sectional view taken on line 3—3 of Fig. 1 in the direction of the arrows.

As shown in the drawing, in the window construction of my invention, the sash frame 15 is provided with a vertical edge 25 to which an edge strip 26 of friction material or the like is preferably secured. The post piece 27 of the window casing is provided with a vertical channel 28 in which the channel strip 10 is adapted to be transversely urged by resilient means such as the springs 11 against the edge of the sash, to seal the sash in the casing as hereinafter more particularly described. The springs 11 are fixed to the post piece 27, said springs preferably having their free ends angularly disposed as at 12 and terminating in flat portions 13 adapted to be freely received within the channel strip 10 to normally urge the latter toward the edge of the sash frame.

As shown in the drawing, the following novel means is provided for displacing the channel strip 10 from the edge of the sash frame against the tension of the springs 11, to enable the sash frame to be vertically reciprocated: A pair of links 16 is positioned on the sash frame adjacent the vertical edge thereof, in spaced relation, by means of

studs 17 or the like fixed to the sash frame and freely passing through apertures in the links. The links are further provided with ears 18 having studs 18' or the like fixed thereto to pivotally secure the ends of the rod 29 to the links. By this arrangement the links 16 will move in unison; the movement of one link will cause the other link to pivot in a corresponding manner.

Each of the links is provided with a roller 19 freely rotatably disposed thereon and adapted, on the rotation of the links about their pivots 17, to be moved against the channel strip 10 as hereinafter more particularly described. In the preferred form of my invention, rotation of the links is attained by providing one of the links with a second ear 20 having a stud 21 to pivotally secure one end of the operating lever 22 to said link, the free end of said lever being preferably flattened to provide a finger piece 24, the lever being pivoted to the sash frame intermediate the free end 24 and pivot 21, preferably by means of stud 23 fixed to the sash frame and freely passing through the lever 22.

In the normal position of the parts, the channel strip 10 will be frictionally maintained against the edge of the sash frame by the tension of the springs 11, and the rollers 19 and the link 16 will be held in their inoperative position shown in Fig. 1. When it is desired to elevate or lower the sash frame, the free end 24 of the operating lever 22 is moved upwardly to the position shown in Fig. 2, thereby pivoting the links 16 downwardly; the rollers 19 displace the channel strip 10 from the free edge of the sash frame 15 and enable the latter to be vertically moved with the rollers 19 rolling on the channel strip 10, so that a minimum of force is required for this operation.

When the sash frame has been moved to the desired position, manual pressure on the free end 24 of the operating lever 22 is released; thereupon the links 16 and channel member 10 will return to the position shown in Fig. 1, responsive to the tension of the springs 11. It will be understood that the above description relative to one vertical edge portion of the sash frame and window casing likewise applied to the opposite vertical portion. The parts described may be manufactured of any desired or convenient alloy, plastic or other suitable material.

From the foregoing disclosure it will be seen that numerous refinements may be incorporated in the construction of the device within the scope of the inventive concept as set forth herein and defined in the appended claims.

It will be noted from Fig. 2 that the channel

member 10 serves as a rail for the rollers 19 while the sash frame 15 is being raised or lowered. It will further be apparent, from an inspection of Fig. 1, that, as the roller-carrying links 16 are pivotally mounted on the sash frame 15 in spaced relation adjacent the vertical edge of the sash frame, the rollers 19 will contact the channel member 10 at spaced points, whereby the sash frame may be vertically reciprocated in an easy, smooth fashion, without danger of wedging in the post pieces. 10

Having thus described my invention, what I claim as new and desire to secure by Letters Patent, is:

1. In a window construction of the class, wherein in a sash frame member having a vertical edge is adapted to be reciprocated relative to a strip member positioned in a vertical post piece channel and yieldably disposed against the sash frame edge, the combination with said window construction, of means to displace the channel strip from the sash frame member edge, said means comprising upper and lower links pivotally mounted on the side face of the sash frame member adjacent the vertical free edge thereof, each of said links including a pair of connected angular arms, a roller carried on each link at the juncture of the angular arms, an operating lever pivotally mounted on the lower portion of the sash frame member, said lever being pivotally connected to the lower link, and a rod connecting the upper and lower links, whereby the rollers will be moved against the strip member in the

channel to displace the same from engagement with the adjacent edge of the sash frame member when the lever is actuated, to enable the sash frame member to be vertically reciprocated.

2. In a window construction of the class, wherein a sash frame member having a vertical edge is adapted to be reciprocated relative to a strip member positioned in a vertical post piece channel and yieldably disposed against the sash frame edge, the combination with said window construction, of means to displace the channel strip from the sash frame member edge, said means comprising upper and lower links pivotally mounted on the side face of the sash frame member adjacent the vertical free edge thereof, each of said links including a pair of connected right angularly disposed arms, a roller mounted on the outer face of each link at the juncture of the angular arms, an operating lever pivotally mounted on the lower portion of the sash frame member; an ear extending from the juncture of the angular arms of the lower link in a downward direction, said lever being pivotally connected to said ear, and a rod connecting the upper and lower links, whereby the rollers will be moved simultaneously against the strip member in the channel to displace the same from engagement with the adjacent edge of the sash frame member, when the lever is actuated, to enable the sash frame member to be vertically reciprocated.

SIEGFRIED E. BLESSIN.
